J. SCHEMINGER, JR

PREHEATING AND DISTRIBUTING DEVICE FOR ROTARY OIL BURNERS

Filed Aug. 20, 1923

Inventor
John Scheminger, Jr.
By Julian Edowee
His Attorney

UNITED STATES PATENT OFFICE.

JOHN SCHEMINGER, JR., OF PROVIDENCE, RHODE ISLAND, ASSIGNOR TO AETNA AUTOMATIC OIL BURNER, INCORPORATED, OF NEW YORK, N. Y., A CORPORATION OF NEW YORK.

PREHEATING AND DISTRIBUTING DEVICE FOR ROTARY OIL BURNERS.

Application filed August 20, 1923. Serial No. 658,443.

To all whom it may concern:

Be it known that I, JOHN SCHEMINGER, Jr., a citizen of the United States, residing at Providence, in the county of Providence and State of Rhode Island, have invented 5 certain new and useful Improvements in Preheating and Distributing Devices for Rotary Oil Burners; and I do hereby declare the following to be a full, clear, and 10 exact description of the invention, such as will enable others skilled in the art to which it appertains to make and use the same.

This invention relates to rotary oil burners, and more particularly to a nozzle of peculiar construction upon which the fuel is delivered from a feed pipe for distribution over the surface of the nozzle and delivery upon a subjacent spray-plate adapted to effect atomization of the oil or other liquid 20 fuel and the admixture of the resultant vapor with air for supporting combustion.

The objects of the invention are to provide simple and efficient means for initially heating or raising the temperature of oil 25 or other liquid fuel and distributing it upon a spray-plate or atomizing device mounted upon a vertical hollow shaft and rotatable with said distributing means; said means comprising a metal body of nozzle-like form 30 having an upwardly extended pointed end and gradually enlarged toward the lower end thereof and having within its lower enlarged portion a gas receiving and distributing chamber from which gas exit ports 35 lead downwardly and outwardly for maintaining a pilot light; a gas feed pipe being provided for delivering gas into said distributing chamber, and a fuel feed pipe having its delivery end arranged over the 40 pointed end of said nozzle so that the liquid fuel is spread over the surface of the nozzle and evently distributed over the surface of the spray-plate and effectually atomized by the combined action of the nozzle 45 and spray-plate.

The invention will first be hereinafter more particularly described, with reference to the accompanying drawings, which are to be taken as a part of this specification, 50 and then pointed out in the claims at the end of the description.

In said drawings, Fig. 1 is a vertical sectional elevation of a fragmentary portion

of a rotary oil burner with a distributing nozzle embodying my invention; and 55

Fig. 2 is a sectional view taken on the line 2—2 of Fig. 1, looking in the direction of the arrows; the parts being shown in inverted position.

Referring to said drawings, in which the same reference characters are used to denote corresponding parts in different views, the letter A denotes a fuel feed pipe leading from any suitable source of supply, and B a distributing nozzle; the delivery end a 60 of said pipe being arranged to deliver liquid fuel upon the pointed end of the distributor, which is mounted upon the upper end of a vertical hollow shaft C within which is stationarily secured a gas feed pipe 70 D. The distributor B consists of a body of metal having an upwardly extended pointed end and gradually enlarged toward the lower end thereof and formed or provided with a gas receiving and distributing chamber b 75 within its enlarged lower portion; a solid mass of metal being left between said chamber and said pointed end to adapt the device to absorb and retain heat enough to pre-heat or raise the temperature of the oil 80 or other liquid fuel delivered by the feed pipe A upon the pointed end of the distributor sufficiently to aid in effecting vaporization. As the oil flows downwardly over the rounded and gradually enlarged surface 85 of the distributor it is spread out in a thin film and distributed over the surface of a subjacent spray-plate E, fixed on the shaft C and adapted in co-operation with the distributing device to effect complete vaporization of the oil and admixture of the vapor 90 with air for consumption by the burner. The upper end of the gas fuel feed pipe D enters the distributing chamber b at the base thereof and has a plug d screwed therein in which there is a minute opening or channel d¹ for discharging a jet of gas into 95 said chamber. The lower flaring portion of the distributor, below the distributing chamber b, has formed therein a plurality or 100 series of gas exit ports b¹ which are preferably inclined outwardly and downwardly with their lower ends arranged to discharge the gas into an annular open space 105 formed between the central portion or hub of the distributor and a depending mar-

100
105

ginal flange b^2 at the lower end or base of the distributor, so that the gas entering said distributing chamber and exuding therefrom through said ports b^1 may not 5 be ignited until it reaches said annular space in which a flame is maintained, spreading outwardly over said flange, and the formation and deposit of soot inside the distributing chamber and the discharge ports is 10 prevented, thus keeping said chamber and ports free and uninterrupted, for the passage of gas therethrough.

The spray-plate E may be of any suitable construction, for example, such as shown 15 in my Patent No. 1,327,256 dated January 6, 1920. As shown, it has a hub-like portion e which is slidably fitted upon the shaft C, preferably by means of a spline and groove connection, to adapt the spray-plate to be 20 readily removed by sliding it upwardly off of the hollow standard. The standard has a shoulder c thereon at the base of the spray-plate upon which the surrounding portion of the latter rests so as to limit its 25 downward movement. The hub-like portion of the distributor B may be similarly secured upon the upper end of the shaft C, so as to cause the two parts to rotate together, or a set screw F (Fig. 2) may be 30 inserted through a hole in the lower portion of the distributor for securing the distributor in a fixed position on the hollow shaft with its hub resting on the hub of the spray plate.

35 In operation, assuming that a gas fed pilot light is burning at the lower end of the distributor, heat will be generated and stored in the mass of metal above the gas receiving chamber sufficient to pre-heat or 40 raise the temperature of the oil or other liquid fuel delivered by the feed pipe A directly over the pointed end of the distributor and spread over the downwardly and outwardly enlarged and rounded surface of the 45 distributor to place the oil in good condition for atomization, and the oil flowing over the surface of the distributor will be distributed evenly or uniformly upon the spray-plate and thus complete atomization and ad- 50 mixture of the vapor with air is effected by the rotation of the spray-plate, and a circle of flame is maintained outside of the gas receiving and distributing chamber and the 55 exit ports leading therefrom, such flame sur-rounding the depending marginal portion or flange b^2 on the lower end of the distributor to prevent the formation and deposit of soot as before stated.

Having thus described my invention, what 60 I claim as new and desire to secure by Letters Patent of the United States is:—

1. A liquid fuel distributor or spreader and pre-heating device for rotary oil burners, or the like, comprising a nozzle-like body having an upwardly extended pointed end and

gradually enlarged toward the lower end thereof and provided with a gas receiving and distributing chamber within its enlarged lower portion, and gas exit ports leading from said chamber through said enlarged end; said body being mounted on a tubular revoluble support carrying a spray-plate underneath said device, and a gas feed pipe extending through said support to said chamber.

2. A liquid fuel distributor or spreader and pre-heating device for rotary oil burners, or the like, comprising a nozzle-like body having an upwardly extending pointed end and gradually enlarged toward the other end thereof and provided with a gas receiving and distributing chamber within its enlarged lower portion, there being a solid mass of heat-retaining metal between said chamber and said pointed end, and gas exit 80 ports leading out of said chamber downwardly through said enlarged end; said body being mounted on a tubular revoluble support carrying a spray-plate underneath said device, and a gas inlet pipe extending 85 through said support to said chamber.

3. In a rotary oil burner, the combination with a vertical hollow shaft, of a spray plate fixed on said shaft near its upper end and a liquid fuel distributor or spreader and pre-heating device of nozzle-like form mounted on said shaft above said spray plate and having an upwardly pointed end and a chambered lower portion with exit ports 90 therein leading downwardly toward said spray plate; the delivery end of a fuel feed pipe being arranged over the pointed end of said distributing and pre-heating device, and a gas feed pipe extending through said shaft into the chamber within said device.

4. In a rotary oil burner, a vertical hollow shaft carrying a spray-plate, a fuel distributor or spreader and pre-heating device mounted on said shaft over said spray-plate; said device consisting of a metal body having a thick upper portion tapering to a pointed end and an enlarged lower portion terminating in a depending marginal extension or flange, and also having a gas receiving chamber therein and gas exit ports 110 leading downwardly from said chamber, for maintaining a pilot light; said extension or flange projecting beyond the delivery end of said gas exit ports, a gas feed pipe extending through said shaft into said gas receiving chamber, and a fuel feed pipe having its delivery end arranged over the pointed end of said body, whereby fuel delivered by said feed pipe on the pointed end of said body is spread over the surface thereof by gravity and distributed over the surface of said spray-plate by centrifugal force.

5. In a rotary oil burner, a vertical shaft carrying a spray-plate or atomizing device 130

- and means for pre-heating and distributing oil over the surface of said spray-plate; said means comprising a metal body having an upwardly pointed end, over which oil may 5 be spread, and gradually enlarging from said end to the lower part thereof, said lower part having a gas receiving chamber therein underlying a solid mass of metal and overlying a centrally disposed annular portion 10 adapted to fit on the upper end of said shaft, and gas exit ports leading from said chamber through said annular portion; said shaft having a gas feed pipe therein leading into said chamber.
- 15 6. The combination in a rotary oil burner with a vertical rotary shaft, of a spray-plate fixed on said shaft near its upper end, a
- pre-heating and distributing device of nozzle-like form mounted on said shaft above said spray-plate and means for supplying 20 oil to the surface of said distributing device; said device having an upwardly pointed end and a chambered lower portion having exit ports therein leading downwardly toward said spray-plate, and a gas feed pipe extending into said chambered lower portion of 25 said device.
- In testimony whereof I affix my signature in the presence of two witnesses.

JOHN SCHEMINGER, JR.
